UNITED STATES PATENT OFFICE

PAUL GENNRICH, OF MAPLE SHADE, NEW JERSEY

WICK CLEANER

Application filed November 14, 1930. Serial No. 495,709.

This invention relates to cutting and scraping devices, and more particularly to cleaners and trimmers for the wicks of oil stoves or lamps.

- 5 One of the objects of the invention is to provide a novel cleaner or trimmer for the wicks of oil burning stoves or lamps by means of which such wicks may be quickly and easily cleaned regardless of their size.
- 10 Another object is to provide a wick cleaner which is simple in structure and inexpensive to manufacture, and is readily adjustable to fit wicks of various diameters.

15 A further object is to provide an instrument of this type embodying a cutter or scraper which is capable of both rotary and radial movements thereby adapting it for use with wicks of any size.

20 These and other objects will appear more fully from a consideration of the detailed description of the invention which follows. Although two embodiments of the invention have been described and illustrated in the accompanying drawing, it is to be expressly understood that this drawing is for the purpose of illustration only and is not to be construed as a definition of the scope of the invention, reference being had for that purpose to the appended claims.

25 In the drawing:

Fig. 1 is a plan view of one embodiment of the present invention shown in conjunction with the wick of an oil stove;

Fig. 2 is a sectional view taken on line 30 2—2 of Fig. 1;

Fig. 3 is a perspective view of the scraper or cutter member shown in Figs. 1 and 2; and

Fig. 4 is a perspective view of a second embodiment of the invention.

40 Referring now to Figs. 1, 2 and 3, there is shown therein a simple and efficient cleaner or trimmer for the wicks of oil stoves or lamps which embodies a novel form of construction enabling it to be used with wicks of various sizes. As shown, a circular frame or spider, indicated generally at 5, constitutes the base or supporting member of the cleaner and comprises a central disc 6 to which are attached, and preferably stamped integrally therewith, a plurality of seg-

mental frame members 7, the outer arcuate edges of same forming a circle whose diameter is in excess of the largest wick with which the cleaner is expected to be used. Between the various segmental members 7 there are formed a plurality of radial slots or grooves 8.

55 Suitably mounted on spider 5 and adapted for radial movement relative thereto in grooves 8 are a plurality of cutters or scrapers, indicated generally at 9. Each of these cutters has a substantially rectangular horizontal arm or base plate 10 and a vertical arm or cutter plate 11. Horizontal base plate 10 is adapted to slide on top of one of segmental frame members 7, while vertical cutter plate 11 extends downwardly within and below radial groove 8. A second horizontal arm or holding down clip 12 may extend parallel to base plate 10 from the face 60 of cutter plate 11 and engage the underside of segmental frame member 7 so as to prevent any vertical movement of the cutter relative to the frame.

65 Vertical cutter plate 11 is substantially 70 M-shaped in elevation having a pair of relatively narrow legs 13 and a wider middle portion 14 which does not extend as far downwardly as do legs 13. The distance between legs 13 is slightly greater than the difference 75 between the inner and outer diameters of the ordinary wick tube, such as that shown at 15, while the width of middle portion 14 is substantially equal to that of the average wick 16. The bottom of middle portion 14 80 is suitably sharpened to form the cutting or scraping edge of the cleaner, while legs 13 are adapted to telescope over the upper end of wick tube 15 thus positioning the cleaner over wick 16 and guiding the cutter in the path of 85 the wick during the cutting operation. Cutters 9 may be made in any suitable manner, but an inexpensive and preferred method of manufacture consists in forming these members first as integral flat metal stampings, having one end shaped to form legs 13 and middle portion 14 of cutter plate 11, cutting one edge of the metal stamping to the shape of holding down clip 12, and then bending 90 said clip and horizontal base plate 10 to a 95

100 integrally therewith, a plurality of seg-

position at right angles to cutter plate 11.

Suitable means are also provided for moving cutters 9 radially in groove 8, thereby varying the distance of said cutters from the center of disc 6 and adjusting the cleaning diameter of the device to fit wicks of any size. In the form shown, an adjusting disc 17, substantially equal in size to central disc 6 of the spider, is rotatably mounted above 5 said central disc on a suitable bushing or spindle 18 which extends centrally through both discs. Pivottally attached to various points about the periphery of adjusting disc 17 is a plurality of connecting links 19, the 10 outer ends of which are also pivotally secured to horizontal base plates 10 of the cutters 9. Any suitable means may be provided for 15 manually rotating adjusting disc 17 relative to the spider such as a pair of angles 20 which 20 are riveted to said disc at diametrically opposite points thereof and constitute convenient means for rotating the disc between the thumb and forefinger.

Suitable means are also provided for rotating 25 the cleaner as a whole, said means comprising, in the form shown, a plurality of horizontal radially disposed arms 21 secured to the underside of central disc 6 of spider 5, each of which is provided with a vertical 30 upwardly extending gripping member 22 adapted to be grasped by the person cleaning the wick.

In using the wick cleaner disclosed in 35 Figs. 1, 2 and 3, spider 5 is first placed vertically over wick tube 15, and then, by means of angles 20, adjusting disc 17 is rotated to move cutters 9 radially inwardly or outwardly to conform to the diameter of wick 16 to be cleaned. When the cutters are thus 40 adjusted to the size of the wick, legs 13 of cutter plates 11 telescope over wick tube 15, and middle portions 14 rest upon the top of wick 16 thus centering the cleaner with respect to the wick in position for scraping or cutting 45 the same. The cleaning operation is then performed by rotating the entire cleaner assembly by means of the upwardly extending gripping members 22. The wick 16 is trimmed and cleaned by the sharpened edge 50 of middle portion 14 of cutter plate 11, legs 13 at the same time serving to remove the carbon which forms on the vertical sides of wick tube 15.

A second and more simple embodiment of 55 the invention is shown in Fig. 4. The cleaner disclosed therein comprises a flat arm 23 on which is slidably mounted a cutter or scraper 24. The latter comprises a substantially rectangular base plate 25, one surface of which 60 is adapted to slide on a flat side of arm 23, a downwardly extending cutter plate 26 having legs 27 and a middle portion 28 corresponding to legs 13 and middle portion 14 of cutter 9 shown in Figs. 1, 2 and 3, and 65 an upwardly extending portion or gripping

member 29. Cutter 24 is slidably secured to arm 23 by any suitable means such as a downwardly turned lip 30 and a pair of upwardly turned lips 31 which engage the opposite side of arm 23 from that on which base plate 25 70 slides. This type of cutter may also advantageously be manufactured from an integral metal stamping, by cutting the various portions to their proper shape when a flat piece, and then bending lips 30 and 31 to the 75 positions shown in Fig. 4.

One end of arm 23 is doubled upon itself to form an eye 32 which acts as the center of rotation or pivot for arm 23 during the cleaning operation. In use, arm 23 is placed over 80 the burner to be cleaned with its flat side in a vertical plane and with eye 32 over the center of the burner or wick. Cutter 24 is then slid inwardly or outwardly along arm 23 until its distance from the center of eye 32 is 85 equal to the radius of the wick, at which time legs 27 telescope over the upper end of the wick tube and middle portion 28 of the cutter rests upon the wick in cleaning position. Holding eye 32 over the center of the wick 90 by any suitable means, either manually or by placing it over a spindle provided with some types of burners, arm 23 is then rotated by means of gripping member 29, and the middle portion 28 of cutter 24 scrapes the wick 95 clean, legs 27 at the same time removing carbon from the wick tube.

There is thus provided by the present invention a novel form of wick cleaner having an adjustable cleaning diameter. The cutter 100 or cutters are easily and quickly adjusted to the diameter of any size wick, and the cleaning operation is readily performed in a simple and efficient manner. Not only is the wick scraped and cleaned, but carbon is also simultaneously removed from the wick tube. The wick cleaner thus provided is simple in structure and inexpensive to manufacture, being especially adapted for quantity production 105 from sheet metal stampings.

It will be obvious that the invention is not limited to the form shown in the drawing but is capable of a variety of mechanical embodiments. For example, adjusting disc 17 and connecting links 19 may be replaced by 115 any suitable means for varying the position of the cutters, as may other means for rotating the cutters be substituted for the vertical gripping members shown. Various other changes, which will now appear to those skilled in the art, may be made in the form, details of construction and arrangement of the parts without departing from the spirit of the invention, and reference is therefore to be had to the appended claims for a definition of the limits of the invention.

What is claimed is:

1. A wick cleaner comprising a frame, a plurality of cutters carried by said frame, means for adjusting the positions of said

- cutters independently of and radially with respect to said frame, and means for rotating said frame and cutters simultaneously.
2. A wick cleaner comprising a substantially circular frame, a plurality of radial grooves formed in said frame, a plurality of cutters slidably mounted in said grooves, means for adjusting said cutters radially with respect to said frame, and means for simultaneously rotating both said frame and said cutters.
3. A wick cleaner comprising a cutter for scraping the wick, means for supporting and rotating said cutter, and means carried by said cutter for guiding the same in the path of said wick during said rotation, said cutter being adjustable relative to said supporting means to wicks of various diameters.
4. A wick cleaner comprising a substantially circular frame, a plurality of radial grooves formed in said frame, a plurality of cutters slidably mounted in said grooves, a disc rotatably mounted on said frame, links pivotally secured to said disc and to said cutters, and means for rotating said cutters.
5. A wick cleaner comprising a substantially circular frame, a plurality of cutters carried by said frame, means for moving said cutters radially with respect to said frame to engage wicks of different diameters, and means for rotating said cutters about the center of said frame.
6. A wick cleaner comprising a supporting member, and a radially adjustable cutter carried thereby, said cutter having a wick-cleaning edge of a width substantially equal to that of the wick to be cleaned and elements carried thereby and adapted to engage the wick to be cleaned for guiding the movement of the cutter with respect to said wick.
7. A wick cleaner comprising a supporting member, and a radially adjustable cutter carried thereby, said cutter having a wick-cleaning edge of a width substantially equal to that of the wick to be cleaned and a pair of downwardly depending legs secured to the extremities of said cutting edge for simultaneously guiding said cutter with respect to the wick and for cleaning carbon from the wick tube.
8. A wick cleaner comprising a frame, a plurality of cutters carried by said frame, means mounted on said frame and connected to said cutters for moving all of said cutters simultaneously toward or away from the center of said frame, and means for rotating said cutters as a unit about the center of said frame as an axis.
9. A wick cleaner comprising a frame, a plurality of cutters carried by said frame, adjusting means mounted on said frame for rotation relative thereto, operative connections between said cutters and said adjusting means whereby relative rotation of the latter with respect to said frame moves all of said cutters simultaneously radially with respect to said frame, and means for rotating said frame, cutters and adjusting means as a unit.
- In testimony whereof I have signed this specification.
